CLAIM

The ornamental design for a liquid dispenser, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever. The following notice applies to this document: Copyright © 2021, Christopher M. Berean and Aaron J. Smith.

The present application is related to U.S. Provisional Patent Application 63/159,449 which was filed Mar. 11, 2021, and which is incorporated herein by reference.

FIG. 1 is a front perspective view of a liquid dispenser;

FIG. 2 is a back perspective view thereof;

FIG. 3 is a left side view thereof;

FIG. 4 is a right side view thereof;

FIG. 5 is a front view thereof;

FIG. 6 is a back view thereof;

FIG. 7 is a top view thereof; and,

FIG. 8 is a bottom view thereof.

The broken lines in the drawings depict environment or structural features that form no part of the claimed design.
